#1 - J. Rosenthal's Design for stamping on
LEAD PENCILS.

Patented April 3, 1860.

Des N° 1230

4-3-1860

EAGLE.

Witness,

John D. Cook,

As. in 1860. Cook,

Inventor,

Jacob Rosenthal

Dec 1230

Joseph Rosenthal, of New York, N.Y.
Assignee to Joseph Reckendorfer, of same place.
Letters Patent No. 1230, dated April 3, 1860.

The schedule referred to in these Letters Patent and making part of the same.

Dec 1230

To all whom it may concern,

Be it known that I, Joseph Rosenthal, of the City, County and State of New York, have invented or produced a new and original design for printing or stamping upon and ornamenting lead pencils and other pencils, and I do hereby declare that the following is a full and exact description of the same.

My design consists of the figure of an eagle, in combination with the word "eagle", placed at its side.

In the drawing the red lines above and below the design indicate the boundaries or outlines of the pencil which may be of any size desired.

The wings of the bird are extended and elevated as if in the act of rising or alighting, and the head is erect and turned toward the observer's right. If the entire breadth of the design be divided into sixty-two (62) parts, the entire breadth of the bird from left tip of the wings is twenty-five (25) parts, its entire height is eight (8) parts, and the height of the head is five (5) parts.

The wing on the right shows an extreme length of twelve (12) parts measured from its junction with the body. The wing on the left shows an extreme length of twelve (12) parts measured from its apparent junction with the body. The upper outline of the wing on the right rises in a right line, at an angle of thirty-two degrees (32°) from the horizontal, for a distance of seven (7) parts, it then curves to the tip on a radius of eight (8) parts.

The point where the straight line joins the curve is denoted by A, and the center of the curvature by B. The breadth of the wing at A. is two parts (2), the breadth at the junction with the finion is three parts.

The wing on the left rises in a right line at an angle of twenty-three degrees (23°) for a length of seven parts (7) it thence curves to the tip on a radius of eight parts (8). The junction of the straight and curved outline is denoted by C, and the center of the curve by D. The breadth of the wing at the point C. is one and a half parts ($1\frac{1}{2}$) from which it gradually increases towards the body where it is three parts (3).

The total length of the emblems in the talons of the bird is eleven parts (11). Eight of these parts lie on the right and three on the left of a line dropped perpendicularly through the center of the head.

The height of the capital letters composing the word "eagle" is six parts (6). The entire length of the word is thirty-four parts (34). The length from the tip of the wing of the bird to the beginning of the lettering is three parts (3).

Des. 1230

My said design is intended to be embossed or imprinted either plain or in gold upon the pencils themselves.

The intention of the said design is to ornament the goods and also to form a mark by which they may readily be distinguished from all other pencils, and be thereby known in the trade.

Having now fully described my design what I claim as new therein and desire to secure by Letters Patent, is the above ornamental design or trademark - composed of a spread eagle and the word "eagle" combined as represented, to be fixed on pencils as above described.

In witness whereof I have hereunto set my hands.

Witnesses.
